UNITED STATES PATENT OFFICE.

FREDERICK CHARLES FORREST, OF SACRAMENTO, CALIFORNIA.

CONTINUOUS SUN BLUE-PRINTING MACHINE.

1,071,724.

Specification of Letters Patent. Patented Sept. 2, 1913.

Application filed April 26, 1912. Serial No. 693,400.

To all whom it may concern:

Be it known that I, FREDERICK C. FORREST, a citizen of the United States, residing at Sacramento, in the county of Sacramento and State of California, have invented a new and useful Improvement in Continuous Sun Blue-Printing Machines, of which the following is a specification.

This invention relates to a continuous sun blue printing machine and the object of the invention is to print blue prints by sun light upon a roll of paper, the paper traveling through the machine and a further object of the invention is not only to print upon the paper but to wash and fix and dry the prints, the prints coming from the machine complete and ready for use.

There are a number of blue printing machines, what are known as the continuous type in which the printing is done by artificial light, said devices being usually constructed for use in connection with an electric light. For printing purposes sun light is far superior to any artificial light, and by reason of its strength the prints can be made much more quickly than by artificial light, thus enabling a sun printing machine to turn out a greater amount of work in a given time than a machine constructed for use in artificial light only.

It is of course understood that artificial light can be employed in connection with my machine, and in this respect it differs from most of the continuous blue print machines which are upon the market as they are constructed so that artificial light only can be employed.

The invention consists of the novel features of construction hereinafter described, set forth in the claims and shown in the accompanying drawings, in which;

Figure 1 is a side elevation. Fig. 2 is a vertical section. Fig. 3 is a front view, parts being broken away and shown in section. Fig. 4 is a plan view of the upper rear portion of the machine, a glass being shown in section. Fig. 5 is a plan view of a lower front corner portion of the machine. Fig. 6 is an enlarged detail sectional view of the lower portion of a curved glass. Fig. 7 is a detail view illustrating certain belts in a drying compartment.

In constructing the device, I employ suitable upright frames 1, substantially trian-

gular in shape and provided in their upper front portions with downwardly and forwardly curved side members 2. These form side members of a frame in which is arranged a curved glass 3. A suitable box 4 is carried at the top and rear of the frames 1 and in such box is adapted to be journaled a roll of blue print paper 5. The box is suitably slotted as shown at 6 in order that the paper may run therefrom.

The construction of the rest of the device will be most readily understood by considering the same in connection with the manner of its operation.

The machine is first situated so that the glass 3 is facing the sun, and it is preferred to arrange the device in a room and permit the sun light to enter through a suitable opening, the rays of light striking squarely upon the glass 3. In order to obtain a subdued light upon the rear portion of the machine, screens, sheets or curtains may be arranged upon opposite sides of the same. After the paper 5 is drawn through the opening 6 and the box 4, the end is secured to narrow belts 7, which draw the paper through the various parts of the machine. Of course any desired means can be employed for getting the paper started through the machine, but the most convenient means is to clamp the free end of the paper to a rod 7a, then secure the rod to the belts by any desired or convenient means. The machine is then set in motion as will be hereafter described and as the blue print paper gradually works down beneath the glass the tracing 8 carrying the drawings to be printed is placed in position between the glass 3 and the blue print paper. A continuous belt 9 travels over a series of rollers 10 and 10a, and firmly presses the tracing 8 of the blue print paper 4 against the under surface of the curved glass 3. I prefer to make the roller 10a adjustable so that it can be used for tightening the belt 9. In order to lengthen or shorten the exposure I provide a curtain 11, which curtain is adapted to slide over the face of the glass 3, lying at the lower end of the glass when rolled up. The curtain is connected to a slidable bar 12, provided with rollers 13, which travel in grooves or guide-ways 14 formed upon the inner faces of the side-members of the exposure frame, and the bar 12 carries spring

pressed rods 15, which also engage said grooves and hold the curtain in an adjusted position, the said curtain working substantially similar to the ordinary curtains employed upon railroad and electric cars.

5. After the blue print paper passes over the lower pulley 10 and leaves the belt 9 it is carried by the narrow belts 7 beneath a series of rubber fingers 16 carried in a row 10 transversely across the lower front portion of the frame and below the exposure glass 3. These fingers separate the tracing from the blue print and after being brushed off the print it falls in folds upon the front of 15 a casing 17, which forms the lower front portion of the machine, and at an opening in the top of which the rubber fingers 16 are placed. The exposure to the sun light is completed when the paper leaves the 20 lower roller 10 and the blue print paper is now ready to be washed. The washing apparatus comprises two perforated water pipes 18, which are arranged in the casing 17. To carry the paper into close proximity 25 to the pipes 18 I employ an endless belt 19, which runs over rollers 20 and 21 mounted in the frame 17, a deflector plate 22 being arranged between said rollers, and serving to protect the rear of the frame 17 from any 30 water which may get past the blue print paper. The blue print paper passes around the lower roller 21 and travels upwardly and by the time it reaches a small roller 23 most of the water has drained from.

35. In making that class of prints known as white line prints, it is not necessary to employ a fixing solution, and the paper would therefore travel from the roller 23 over a roller 24 and out through the rear of the 40 frame 17 to the drying compartment. But where a blue line print is to be made, it is necessary to give it a bath in a fixing solution after being washed. This solution is held in a tray 25 in the frame 17. This 45 tray is adapted to be raised and lowered by hand, and by elevating the same the paper traveling under the roller 24 will be submerged in the fixing bath.

It will be noted that the narrow belts make 50 a complete circuit of the device running from the upper roller 10 downwardly over the lower roller 10, then over the rollers 20, 21, 24, both rollers 31, to the roller 32, over the roller 33, and back to the upper roller 10. The paper is carried by these belts as 55 far as the roller 32, at which point the paper passes from the device between the roller 32 and the second roller 31, the belt 7 continuing its course back to the upper 60 roller as described.

Arranged in the drying compartment is a suitable heater comprising a gas pipe 26 provided with burners and a suitable hood having a broad flat top above which the 65 paper fastens. Arranged above the paper is

a condensing hood 28 around the interior of which is a trough 29 so that steam or moisture rising from the paper and condensed upon the underside of said hood will run down into said trough instead of falling back upon the paper. To support the paper through the drying compartment I cannot employ wide belts as in the case of belts 9 and 19 and I therefore employ a large number of narrow belts 30 which run over rollers 31. By employing these narrow belts spaced apart the heat radiated from the top of the burner casing 27 can pass between said belts and come into contact with the underside of the blue print paper. After 70 passing above the burner and below the hood the paper passes out at the rear of the machine between one of the rollers 31 and the pulley 32, and the belts 7 continuing upwardly and over another pulley 33, and 75 thence back over the upper roller 10. It will be noted therefore that the continuous belts 7 carry the blue print paper through the entire machine and lead it successively from the belt 9 to the belt 19 and thence to the belts 30. In order to run the belts a suitable motor 34 having on the motor shaft a pulley 34^a is employed and a friction disk 35 on a shaft 38 is driven from the pulley 34^a and a second friction disk 36 is arranged 80 parallel to the disk 35 but with its shaft 37 in a lower plane than the shaft 38. A non-rotatable vertical shaft 39 carries an adjustable friction wheel 40 loose upon the shaft the periphery of which travels upon 85 the sides of the disks 35 and 36. The friction wheel 40 is held between collars 40^a secured upon the shaft 39 by suitable set screws. A spring 38^a on shaft 38 holds the disk 35 against the friction wheel 40. Upon 90 the shaft 37 is formed a worm 41, which meshes with a gear wheel 42 fixed on a shaft 42^a. On one end of the lower roller 10 is a small gear wheel 43 which meshes with a small gear wheel 43^a on the shaft 42. At opposite ends of the lower roller 10 and the roller 20 I arrange sprocket wheels 44 and 44^a. Sprocket chains 45 run over said 95 sprocket wheels and transmit motion from the lower roller 10 to the lower roller 20. A second sprocket wheel 46 is mounted on the shaft 42^a of the gear wheel 42 and a sprocket chain 47 runs from said sprocket wheel 46 to a sprocket wheel 48 at the end of one of the rollers 31.

The shaft 39 is movable vertically, its 100 position being regulated by means of a pivoted lever 49, one end of which is loosely connected to the upper end of the shaft 39, and the handle end portion of the lever 49 works over a slotted bracket 50 to which the lever can be locked by means of a suitable winged nut 51. This lever is connected to a pointer 52 which slides along a scale 53 laid off upon a rear side member of the 105 110 115 120 125 130

frame 1, said scale indicating the speed with which the blue print paper is being fed to the machine.

To tighten the belt 9 I provide the roller 10^a with adjustable bearings as shown at 54. Similar bearings 55 are provided for the lowest roller 31 in order to regulate tension of the belt 30.

It will be noted that the washing device 10 is so constructed that the blue print paper is sprayed only upon the sensitized side, and consequently as only one side of the paper is wet it will dry more quickly than if it was drawn through a bath and both sides 15 wet.

It will also be noted that as the paper passes to the drying compartment the exposed and sprayed side will be downward and consequently toward the heater, so that 20 the heat radiated from the top of the heating casing will act directly upon the wet side of the blue print. This also assists in causing the paper to dry very quickly. It will also be noted that by regulating the 25 speed at which the blue print paper and the tracing are carried through the machine the length of exposure, that is the time occupied in passing beneath the glass 3 will be regulated. Furthermore by means of the 30 curtain the paper can be more or less shaded, thereby allowing for variations in the strength of the light caused by the passing of small clouds, thus making the exposure practically uniform for all parts of the 35 sheet.

What I claim is:

1. In a machine of the kind described comprising an exposure, a washing and a drying compartment, continuous belts running through all of said compartments and adapted to carry a sheet of blue print paper successively through said compartments, a tracing paper being carried through the exposure compartment and a series of rubber 45 fingers arranged at the entrance to the washing compartment and adapted to brush the tracing paper from the blue print paper.

2. A blue printing machine comprising a curved frame, a curved glass plate in said frame, narrow belts adapted to travel beneath the marginal portions of said frame and to carry a sheet of blue print paper and a tracing through said exposure compart-

ment, and a continuous belt adapted to travel beneath said glass and to hold the 55 blue print paper and the tracing paper in close contact with said glass, and a curtain slidably mounted upon the outer face of said glass.

3. A printing device of the kind described comprising an exposure compartment, a washing compartment and a drying compartment, a series of continuous belts arranged in each compartment, and adapted to receive a sheet of blue print paper and 60 support the same while passing successively through said compartments, and continuous narrow belts adapted to travel through all of the compartments and convey the blue print paper from one compartment to the 70 other.

4. A printing device of the kind described comprising an exposure compartment, a washing compartment and a drying compartment, means for conveying a sheet of 75 blue print paper successively through said compartments, and a fixing bath arranged between the washing and drying compartments and adapted to be moved into or out of engagement with said paper.

5. A blue print device of the kind described comprising exposure, washing and drying compartments, means for feeding a sheet of blue print paper through all of said compartments, the sensitized side of said 85 paper being uppermost in the exposure compartment and being upon the underside in the drying compartment and means arranged in the washing compartment for spraying the sensitized side of said paper 90 only.

6. A device of the kind described comprising an exposure, a washing and a drying compartment, continuous belts adapted to convey a sheet of blue print paper successively through said compartments, and a plurality of parallel continuous belts traveling in the drying compartment and adapted to support the said blue print paper above the source of heat, said last mentioned belts 100 being spaced apart.

FREDERICK CHARLES FORREST.
